UNITED STATES PATENT OFFICE

92,880

DESIGN FOR A SAUCEPAN

William T. Christman, Mount Lebanon, Pa., assignor to Federal Enameling & Stamping Company, McKees Rocks, Pa., a corporation of Pennsylvania

Application November 14, 1933, Serial No. 49,714

Term of patent 14 years

To all whom it may concern:

Be it known that I, WILLIAM T. CHRISTMAN, a citizen of the United States, residing at Mt. Lebanon, Allegheny County, Pennsylvania, have invented a certain new, original, and ornamental Design for Saucepans, of which the following is a specification, reference being had to the accompanying drawing, forming a part hereof.

The figure represents a perspective view of the pan embodying my design.

I claim:

The ornamental design for a saucepan substantially as shown.

In testimony whereof, I have hereunto subscribed my name this 13th day of November, 1933.

WILLIAM T. CHRISTMAN.
